FIG. VI.

INVENTOR:

CHARLES RUPP

by William E. Craig
Attorney.

UNITED STATES PATENT OFFICE.

CHARLES RUPP, OF GERMANTOWN, PENNSYLVANIA, ASSIGNOR TO J. S. THORN COMPANY, OF PHILADELPHIA, PENNSYLVANIA, A CORPORATION OF PENNSYLVANIA.

METAL WINDOW FRAME AND SASH.

Application filed June 11, 1924. Serial No. 719,283.

To all whom it may concern:

Be it known that I, CHARLES RUPP, a citizen of the United States, residing at Germantown, in the county of Philadelphia and State of Pennsylvania, have invented a certain new and useful Improvement in Metal Window Frames and Sash, whereof the following is a specification, reference being had to the accompanying drawings.

10 My invention relates to structures wherein sash are provided with laterally projecting plates extending in the same plane as the sash, through vertical slots in hollow jambs, so as to substantially prevent the passage of air between such sash and jambs. Ordinarily, such sash are provided with primarily separate means, within the jambs, for limiting the lateral play of the sash with respect to the jambs. On the contrary, in accordance with my present invention, the transverse movement of the sash is limited by ledges upon the outer faces of such sash frame plates, encountering the outer faces of the jamb members. Moreover, such plates 25 have lugs, punched to project therefrom, transversely to the plane of the sash, but in unitary relation with said plates, with means for attaching thereto flexible connectors for sash weights. Incidentally, I find it convenient to form such plates of angle bars which are rolled to the proper form, as distinguished from the devices of the prior art which are formed of thin pressed sheet metal; the advantage of the rolled sash 30 plates being that they may be made of much greater thickness and, consequently, more durable than the prior devices which must be comparatively thin to permit them to be pressed to the desired form.

40 As hereinafter described, the rolled sash plates in accordance with my invention constitute the main parts of the sash frames, being offset in two steps, in planes parallel with the sash glass, one step being adapted to receive the glass with the plastic material holding it, and the other step being adapted to receive, within the thickness of the sash, a face plate which retains the glass in the sash; the shoulder at the edge of that step determining the position of said face plate, so that the sash may be quickly assembled by comparatively unskilled labor.

Moreover, in accordance with my invention, the laterally extending sash plates aforesaid, with their transversely extending

weight connector lugs, are each inclosed in a chamber formed in connection with the "cheek" of the frame, viz, the sheet metal parts of the jamb which are directly opposed to the edges of the sash. Such construction 50 serves to suppress drafts of air through the jamb.

Furthermore, a preferable adjunctive feature of my invention is a specific construction of muntin, including a heavy rolled 55 T-bar rigidly connected at its opposite ends to the sash plates aforesaid and detachably connected with a thin face plate, the latter being set in the same plane as the other face plates in the sash, and said muntin bar and plate adapted to hold the edges of the glass with the plastic material retaining the same.

My invention includes the various novel features of construction and arrangement hereinafter more definitely specified.

In said drawings, Fig. I is an outside elevation of two window sashes, in the relation in which they are mounted in a window frame.

Fig. II is a fragmentary elevation of a portion of one of the right hand sash members shown in Fig. I, at the region of the weight connecting lug, but on a larger scale.

Fig. III is a fragmentary elevation of the right hand edge of the sash plate as shown 70 in Fig. II.

Fig. IV is a fragmentary horizontal sectional view of said sash plate, taken on the line IV in Figs. I, II and III.

Fig. V is a fragmentary plan sectional view of a metal window frame and sash embodying my invention and taken on the line V, V in Fig. VI.

Fig. VI is a fragmentary vertical sectional view of a metallic window frame and sash 95 embodying my invention, in connection with the wall of a building.

Referring to Fig. I, as viewed from outside, the upper sash 1 and lower sash 2 are precisely alike but are overlapped intermediate of the height of the window, as indicated in Fig. VI. The opposite side members 4 and the top rail 5 and the bottom rail 6 of each sash are each formed of a rolled steel plate of the cross section indicated in Fig. IV, mitered and united at their corners, conveniently by welding operations. Each of said sashes also preferably includes a muntin bar 8 of the T-shaped cross section indicated in section in Fig. V, and also 100 105 110

integrally united, conveniently by welding, to the top and bottom rails 5 and 6. Each of said sash side members 4 has two lugs 9 and 10 punched to project therefrom, transversely to the plane of the sash, i. e., in substantially horizontal planes, but in unitary relation with said plates. Each of said lugs 10 is provided with means for attaching thereto flexible connectors for sash weights, 5 including a circular punched hole 11 through the lug, as indicated in Fig. IV, with respective chain links 12 extending therein as indicated in Fig. V. However, it is unnecessary to provide such openings 11 in the lugs 10 which merely serve as guides for the sash in connection with the window jambs.

Referring to Fig. IV, each of the sash plates 4, 5 and 6 is offset to form two steps 14 and 15, in planes parallel with the plane 20 of the glass 16. As shown in Fig. V, the step 14 receives the edge of the glass 16 and the plastic material 17 for securing said glass in the sash, and said glass and such material are retained in the sash by the vertical face plates 18 shown in Fig. V, in conjunction with the other face plates shown in Fig. VI, viz, the upper face plate 20 of the upper sash; the lower face plate 21 of the upper sash; the upper face plate 22 of the lower sash; and the lower face plate 23 of the lower sash. It may be observed that the positions of all of said face plates are determined by the respective shoulders 24 on said sash frame plates 4, 5 and 6, and 35 that said face plates are thus received and held within the thickness of the sash, conveniently by flat headed screws connecting them with the respective sash frame plates. As shown in Fig. VI, said face plate 21 on 40 the rail 6 of the upper sash, is conveniently formed in unitary relation with the channel 25 which cooperates with the flange 26 of the channel bar 27 on the rail 5 of the lower sash 2, to form a substantially wind tight 45 joint at such meeting rails of said sashes, when the latter are in the normal closed position indicated in Figs. I and VI.

As indicated in Fig. V, the inner vertical edges of said panes of glass 16 are secured in 50 the plastic material 17 in the muntin bars 8 and retained by the face plates 28 which are conveniently detachably connected with said bars 8 by the screws 29.

The transversely extending flanges 31 on 55 said sash plates 4 extend through respective slots in the cheek of the hollow jamb 32 which cheek, as shown in Fig. V, includes the central vertical parting bar channel 33, the inner weathering bar 34 and the outer 60 weathering bar 35, all rigidly connected with said jamb 32. As shown in Fig. V, said jamb 32 is formed of a single piece of pressed sheet metal having its inner edge doubled and offset as indicated at 37 to 65 form a seat for said cheek members 33 and

34 which are rigidly connected therewith, conveniently by bolts 38. Said jamb 32 is folded at its outer corner to form the anchor flange 39 which is embedded in the cement 70 members 41 and 42 which are preferable masonry. The outer edge of said jamb 32 is folded to form the seat 45 to which said outer weathering bar 35 is conveniently rigidly connected by the bolts 46. Said 75 jamb 32 is also folded to form the channel 47 for resilient engagement with the flange 48 on said parting bar channel 33 to form a wind tight joint therewith without riveting. It is to be understood that the flange 48 of 80 said parting bar channel 33 is inserted in said jamb channel 47, in resilient engagement therewith, before said member 33 is rigidly connected to the jamb by said bolts 38, thus lessening the labor and the cost of 85 assembling the structure.

It may be observed that the construction above described is such as to form respective substantially wind tight chambers 50 and 51 in the cheek of each jamb to receive 90 the sash flanges 31 and the lugs 9 and 10 projecting therefrom.

Referring to Figs. V and VI, it is to be understood that chains or other flexible connectors 53 extend from said links 12 over 95 respective sheaves 54 to the respective sash weights 55 which are free to rise and fall in the hollow of the respective jambs 32 but are separated by parting strips 56. As shown in Fig. VI, said sheaves 54 are conveniently journaled in frames 57 which are riveted in the upper portions of said jambs or otherwise rigidly connected therewith.

As shown in Fig. VI, the head section of 105 the window frame includes two members 58 and 59 of pressed sheet metal. The main member 58 has the inwardly extending angle channel 60 in its lower portion, inclined to the plane of the sash, to receive and engage the upwardly extending flange 61 on 110 the top rail 5 of the upper sash in substantially wind tight relation. Said member 58 is folded at its upper front edge to form an anchor flange 62 extending between the lintel members 63 and 64, the former being 115 adapted to hold the portion of the wall 65. Said head member 58 has at its upper edges, flanges 66 and 67 forming seats for said member 59, which is a cap plate extending beneath said lintel member 64 and another 120 lintel member 68 and may be sealed in connection therewith by the plastic material 69 which extends in the interstices between the window frame and said wall members. Said head section is also provided with the weathering bar 71, which is similar in cross section to the bar 35 shown in Fig. V and is conveniently rigidly connected 125 with said head member 58 by the bolts 72.

As shown in Fig. VI, the sill section of 130

the window frame is formed of the hollow metal channel 74 having inwardly turned flanges 75 and 76 respectively at its outer and inner bottom edges, which rest upon the 5 wall members 77 and 78 to which said sill member is conveniently connected by the plastic material 80. Said sill member 74 has the shoulder 81 which is slightly inclined outward for contact with the lower 10 flange 82 on the bottom rail 6 of the lower sash, and said sill member 74 has the second shoulder 83 similarly inclined for contact with the rail 85 which is rigidly connected 15 with said lower sash member. It is to be understood that the arrangement above described is such as to make a substantially tight joint between the sill and the lower sash, when the latter is closed in the position shown in Fig. VI.

20 In order to facilitate manipulation of said sashes 1 and 2, I find it convenient to provide them with respective handles 87 and 88 which are rigidly connected therewith.

25 It is to be particularly noted that the lateral play of said sashes is limited by the ledges 89 and 90 which are offset so as to limit such movement by contact with the cheek members of the respective jambs 32.

30 That is to say, the upper sash 1 has the ledge 89 adapted to encounter the weathering strip 35 of said jamb cheek, and the sash 2 has the shoulder 90 adapted to encounter the cheek member 33. Although as 35 shown in Fig. V, said lugs 9 and 10 extend in such position as to appear to limit the movement of the sash outward with respect to said jamb cheek members 34 and 35; they do not present sufficient surface to 40 withstand the wear incident to the opening and closing movement of said sash, whereas, the ledges 89 and 90 aforesaid extend the full height of the respective sashes and thus afford ample wearing surface.

45 Although I have found it convenient to mount the sash shown in Fig. I in window frames of the specific construction shown in Figs. V and VI, it is to be understood that I do not desire to limit myself to such embodiment thereof. Moreover, the window frame construction shown in Figs. V and VI has advantages which are independent of the specific details of construction of the sash above described.

55 Therefore, I do not desire to limit myself to the precise details of construction and arrangement herein set forth, as it is obvious that various modifications may be made therein without departing from the essential features of my invention, as defined in the appended claims.

I claim:

1. The combination with a metal window frame having opposite slots extending vertically in the jamb cheeks thereof; of a

sash frame having opposite vertical plate members fitted to extend through the respective slots in sliding relation therewith; each of said sash frame plates having a ledge extending vertically thereon and offset in opposition to the respective jamb cheek, arranged to limit transverse movement of the sash with respect to the window frame; said sash frame plates being offset to form a recessed step parallel with the 75 plane of the sash; and a glass panel mounted in the stepped portion of said sash plates.

2. The combination with a metal window frame having opposite slots extending vertically in the jamb cheeks thereof; of a sash frame having opposite vertical plate members fitted to extend through the respective slots in sliding relation therewith; each of said sash frame plates having a ledge extending vertically thereon and offset in opposition to the respective jamb cheek, arranged to limit transverse movement of the sash with respect to the window frame; said sash frame plates being offset to form 80 two recessed steps, of different depths, parallel with the plane of the sash; a glass panel mounted in the deeper stepped portion of said sash plates; a face plate mounted in the shallower stepped portion of said 85 plates within the thickness of the sash; marginal shoulders on said sash frame plates at the outer edge of the shallower recessed portions thereof; whereby proper location of said face plate may be determined; and 90 means detachably securing said face plate in rigid relation with said sash frame plates.

3. A metal window sash formed of four plates of similar cross section in quadrangular relation, mitered and welded at their corner junctions; each of said plates having three plane portions in parallel relation with each other and with the plane of the sash including an outer flange, an inner 100 shallow recessed stepped portion, and an innermost deeper recessed stepped portion; a panel fitted in said deeper recessed portion; a face plate fitted in said shallower recessed portion and adapted to retain said 105 panel; said face plate having, at the meeting rail of the sash, a flange portion projecting from the plane of the sash for engagement with another sash.

4. A metal window sash formed of four plates of similar cross section in quadrangular relation, mitered and welded at their corner junctions; each of said plates having three plane portions in parallel relation with each other and with the plane of the sash, including an outer flange, an inner shallow recessed stepped portion, and an innermost deeper recessed stepped portion; a panel fitted in said deeper recessed portion; a face plate fitted in said shallower recessed 120 portion.

- tion and adapted to retain said panel; said face plate having, at the meeting rail of the sash, a flange portion projecting from the plane of the sash for engagement with another sash; said meeting rail flange being inclined to the plane of the sash; whereby wedging engagement may be effected between a pair of sashes forming a substantially wind tight joint.
10. 5. The combination with a metal window frame having slots extending in the same plane in the head section and jamb cheeks thereof; of a quadrangular sash frame, comprising a marginal flange projecting from all sides thereof in the plane of the sash; the flange portions of the side members of the sash frame continually extending within said jamb cheek slots; the flange upon the top rail of said sash frame being adapted to extend within and be withdrawn from the slot in said head section, in accordance with the position to which said sash is adjusted; and ledges upon opposite vertical sides of said sash frame, offset transversely to the plane of the sash, arranged to encounter the adjacent jamb cheeks and limit the transverse movement of the sash with respect to said jambs; a similar ledge at the top rail of said sash arranged to encounter the lower surface of said head section and limit the upward movement of said sash.
6. The combination with a metal window frame having slots extending in the same plane in the head section and jamb cheeks thereof; of a quadrangular sash frame, comprising a marginal flange projecting from all sides thereof in the plane of the sash; the flange portions of the side members of the sash frame continually extending within said jamb cheek slots; the flange upon the top rail of said sash frame being adapted to extend within and be withdrawn from the slot in said head section, in accordance with the position to which said sash is adjusted; and ledges upon opposite vertical sides of said sash frame offset transversely to the plane of the sash, arranged to encounter the adjacent jamb cheeks and limit the transverse movement of the sash with respect to said jambs; a similar ledge at the top rail of said sash arranged to encounter the lower surface of said head section and limit the upward movement of said sash; said head section having an inwardly extending angle channel portion, at the edge of the slot therein, inclined with respect to the plane of the sash and adapted to be encountered by the top flange on the sash in substantially wind tight relation.
60. 7. A metal window sash having a marginal frame plate with a plane flange projecting therefrom in the plane of the sash at the outer edge thereof; the inner edge of said sash frame plate being offset to form a recessed step, parallel with the plane of the sash; a muntin bar of T-shaped cross section rigidly connected with the top and bottom rails of said sash frame, with its central rib extending in the recessed portion of said frame; glass panels mounted in the recessed portions of said marginal frame plates and muntin bar; and face plates respectively fitted in said frame plates and to said muntin bar, within the thickness of the sash, and arranged to hold the glass therein.
8. A sash frame formed of rolled steel bars each having three parallel plane portions in offset recessed relation with each other, and a muntin formed of a T-shaped rolled steel bar having its opposite ends rigidly connected with opposite side members of said sash frame, with its rib extending within the recessed offset portion of said sash frame and of less extent than the thickness of the sash.
9. A sash frame formed of rolled steel bars each having three parallel plane portions in offset recessed relation with each other, and a muntin formed of a T-shaped rolled steel bar having its opposite ends rigidly connected with opposite side members of said sash frame, with its rib extending within the recessed offset portion of said sash frame and of less extent than the thickness of the sash; and face plates respectively connected with the rib of said muntin bar and in the shallower recessed portion of said frame plates; said face plates being within the thickness of the sash.
10. In a metal window frame, a jamb member formed of hollow pressed sheet metal having a portion folded at the outer front corner thereof, parallel with the window frame, forming an outwardly projecting anchor flange, for engagement with the building; the front inner edge of said jamb member being folded to form a vertical channel transverse to the plane of the frame; the back edge of said jamb member being doubled and offset to form a vertically extending seat; a jamb cheek including a central vertical parting bar channel formed of pressed sheet metal having its inner plane edge fitted to said seat and having its outer vertical edge inclined to the plane of said frame and fitted in said jamb channel in resilient substantially wind tight relation therewith; and means rigidly connecting said cheek member in and at said seat; whereby said cheek member is secured, without other attaching means, at its outer edge.
11. In a metal window frame, a jamb member formed of hollow pressed sheet metal having a portion folded at the outer front corner thereof, parallel with the window frame, forming an outwardly projecting anchor flange, for engagement with the building; the front inner edge of said jamb member being folded to form a vertical channel transverse to the plane of the frame; the back edge of said jamb member being doubled and offset to form a vertically extending seat; a jamb cheek including a central vertical parting bar channel formed of pressed sheet metal having its inner plane edge fitted to said seat and having its outer vertical edge inclined to the plane of said frame and fitted in said jamb channel in resilient substantially wind tight relation therewith; and means rigidly connecting said cheek member in and at said seat; whereby said cheek member is secured, without other attaching means, at its outer edge.

- channel transverse to the plane of the frame; the back edge of said jamb member being doubled and offset to form a vertically extending seat; a jamb cheek including a central vertical parting bar channel formed of pressed sheet metal having its inner plane edge fitted to said seat and having its outer vertical edge inclined to the plane of said frame and fitted in said jamb channel in resilient substantially wind tight relation therewith; and means rigidly connecting said cheek member in and at said seat; whereby said cheek member is secured, without other attaching means, at its outer edge; and a weathering strip having a flange extending in said seat and secured thereto by the same attaching means.
12. A metal window frame jamb having parallel vertical slots therein for respective sash flanges, and substantially closed chambers, within the jamb, respectively local to said slots, formed of primarily separate pieces, including a main hollow pressed member, a vertical parting bar channel having one edge rigidly connected with said main jamb member, and a weathering strip, held by the same connecting means, and having its opposite edge resiliently connected with said main jamb members.

13. A rolled steel sash bar having three parallel plane portions in offset recessed relation with each other.

In testimony whereof, I have hereunto signed my name at Philadelphia, Pennsylvania, this 27th day of May, 1924.

CHARLES RUPP.
